UNITED STATES PATENT OFFICE.

ALEXANDER WINTON, OF LAKewood, OHIO, ASSIGNOR TO THE WINTON GAS ENGINE & MANUFACTURING COMPANY, OF CLEVELAND, OHIO, A CORPORATION OF OHIO.

EXPLOSIVE-ENGINE.

1,260,847.

Specification of Letters Patent. Patented Mar. 26, 1918.

Application filed September 26, 1914. Serial No. 863,70.

To all whom it may concern:

Be it known that I, ALEXANDER WINTON, a citizen of the United States, residing at Lakewood, in the county of Cuyahoga and 5 State of Ohio, have invented certain new and useful Improvements in Explosive-Engines, of which the following is a specification.

This invention relates to improvements in 10 internal combustion motors and particularly to devices of that character using fuel oil and operating under high compression.

More specifically the invention relates to 15 a suitable water circulating system for an internal combustion motor, to structural details in conjunction with the exhaust and the water circulating system, and to other features hereinafter set forth in the following description, drawings and claims.

20 Referring to the drawings, Figure 1 is a side elevation of the engine, designated hereinafter as the cam shaft side; Fig. 2 is an elevation of the exhaust side showing parts broken away; Fig. 3 is an end elevation of 25 the first cylinder and is a view taken behind the governor structure with parts broken away to more clearly set forth the details; Fig. 3' is a sectional view through the fuel pump; Fig. 4 is a top plan view of the engine; Fig. 5 is a sectional view through one 30 of the heads and upper part of the cylinders showing the valve construction; Fig. 6 is a view partly in elevation and partly in section showing the fuel pump mechanism; Fig. 35 7 is a view of a unit of two cylinders, one being shown with the head removed the other with portions of head broken away; the exhaust head and portion of the cam shaft being shown partially in plan and partially in section; Fig. 8 is a view of the upper 40 portion of two adjacent cylinders with parts broken away to show the circulating system and the air inlet; Fig. 9 is an elevation of a portion of the cam shaft side of the motor 45 setting forth the oiling system; Fig. 10 is a section through the cam shaft and trough; and Fig. 11 is a top plan view of a section of the cam shaft and trough.

In carrying out my invention any pre- 50 ferred form and construction of parts may be employed so long as they possess the necessary characteristics, but I have shown one arrangement which is effective, and in such

embodiment the several parts will be described, and the complete operation will 55 then be given.

Crank case structure.

The crank case structure may be of any 60 desired construction, and its details together with the crank shaft and its bearings are not shown, for the reason that they form no important part of the invention, and may be of any preferred arrangement.

The crank case structure itself comprises 65 a lower base portion 1 mounted upon a suitable structure 2 and supporting the upper crank case member 3. These parts inclose a suitable crank shaft upon which is mounted a balance wheel 4. The forward portion 70 of the crank case is adapted to receive suitable gearing and another mechanism for operating a suitable air pump structure 5, the details of which form no important part 75 of the invention, it only being important that it should furnish air under pressure for the mixture which is inserted through the fuel valve to be described. The crank shaft is also connected through suitable gearing to a governor 6 shown in elevation merely, because its details do not enter into the combination. This governor, however, is provided with the usual grooved member 7 for actuating the inlet of fuel as will later appear.

80 The upper half 3 of the crank case is provided on the exhaust side of the engine in the upper corner with a longitudinally disposed port 8 adapted to be connected to a suitable pipe 9 preferably leading to a point 90 out of the building so as to muffle the noise of the air intakes which are connected to this channel. At each of the cylinders there is a port 10 for a purpose to be described.

Cylinder structure.

95 There are preferably six cylinders employed, and each comprises a main cylinder body 11 provided with a suitable water jacket 12 and a lower supporting flange 13 100 adapted to be secured to the upper member 3 of the crank case. Each cylinder is open at its upper end, as shown in Fig. 7, and is faced off to receive the cylinder head structure to be described. At the upper end of 105 the cylinder the face is cut away at 14 at

diametrically opposed points to allow for the operation of the valves, as will later appear. On the exhaust side each cylinder jacket is provided with a finished portion 15 provided with an outlet port 16 for a purpose to be described. At a lower point on the same side of the cylinder, the jacket is provided with a finished boss 17 connected to a flange 18 in turn connected to a hand 10 operated valve 19, this valve in turn being connected to a water inlet manifold pipe 20. Each cylinder is provided on the exhaust side and preferably toward one side with a cast air inlet member 21 having a port 22 15 therein communicating with one of the ports 10 and opening out at the top, as shown in Fig. 7, the upper end of this member being finished with the top of the cylinder. Diametrically opposed to this air inlet member 20 is a pet-cock or relief valve 23 of any desired structure, and this is in communication with the interior structure through a suitable port 24, shown in dotted lines in Fig. 7. This pet-cock and relief valve may be utilized for any of the purposes to which such 25 devices are applicable.

Cylinder head.

Each cylinder is provided with a head 25 which is hollow to form a water space. Integral with the wall of the head are suitable vertically disposed ribs 26 provided with openings 27 for receiving suitable bolts or studs for holding the head in place. The 30 head is provided upon its bottom with an exhaust valve opening 28 having a seat 29 and with an air inlet opening 30 provided with a seat 31. A suitable exhaust housing 32 extends into the hollow head and establishes communication with the opening 28 35 and an opening 33 in the exhaust elbow 34 extending out beyond the side of the cylinder. This elbow and housing are formed integral with the head and the head itself and the 40 elbow are formed integral with a water jacket elbow portion 35, these parts terminating in a horizontally disposed flange 36 beyond the side of the cylinder.

The opening 30 communicates with an air 45 inlet housing 37 formed integral with the head and extending out and in communication with an air inlet elbow 38, the lower edge of said elbow being finished and being flush with the lower edge of the head and 50 arranged in position to communicate with the opening 22 in the air inlet member 21. The water jacket portion of the exhaust elbow structure is provided with suitable ports 39, preferably three in number, extending 55 through the flange 36, as shown in Figs. 7 and 8. Each head 25 is also provided with a water outlet connection 40 terminating in a horizontally disposed flange 41, as shown in Figs. 1, 3 and 7.

Between the air inlet valve and the ex-

haust valve the head is provided with a solid guide portion 42, as shown in Fig. 5, and this guide portion receives a primary fuel and air mixing valve structure comprising a tubular member 43 having at its lower end a 70 valve seat 44, and at its upper end a flange 45 adapted to be secured to the cylinder. Above this flange is a suitable stuffing box sleeve portion 46 adapted to receive a stuffing box structure which surrounds a valve stem 75 48. This valve stem is provided at its lower end with a valve 49 for engaging the seat 44. Above the flange 45, the tubular member is provided with a suitable air inlet 50 and a fuel inlet 51 and between these inlets and the 80 valve 49, the valve stem 48 is provided with a plurality of baffling flanges and recesses which thoroughly mix the fuel and a certain volume of air for the primary mixture. This structure, however, forms no part of 85 this invention but is included in other applications already on file—viz. the applicant's copending application for valve structures for internal combustion motors, filed April 27, 1914, Serial No. 834,738, and his application for mixing and admission valve structures for internal combustion motors, filed June 25, 1914, Serial No. 847,271. The valve 49 is normally held seated by a spring 52 engaging the stuffing box structure at one 95 end and a washer 53 held in place with respect to the valve stem by a split ring structure 54 engaging in a groove 55 in the valve stem.

The exhaust opening 28 and the air inlet 100 opening 30 are both provided with valve mechanism, and since the mechanism in both instances is the same a description of one will suffice for both. Each valve structure comprises a valve stem 56 guided in the head 105 and having at its lower end a mushroom valve 57 adapted for engagement with the seat. The upper end of the stem is guided in the head and is surrounded by a spring 57a, this spring engaging the head at one end 110 and at the other end engaging a washer 58 held in place upon the stem by a split ring 59 arranged in a groove 60 in the stem.

Each cylinder head is held in alignment upon its corresponding cylinder by a reduced portion 61 engaging within a recess 62 formed in the upper part of the cylinder, and is forced into place by suitable bolts or studs 63. When the piston head is in place, the opening in the air inlet elbow 38 communicates with the opening 21 as hereinbefore stated.

Exhaust manifold and water circulating system.

So far as the exhaust manifold structure is concerned, the cylinders are arranged in pairs, and each pair is provided with a manifold having a water circulation about the same, and each of these manifold units 130

or sections consists of an outer casing 64 provided at each end with a flange 65 and on the side toward the cylinders with other flanges 66, the latter being provided with openings 67 communicating with the openings 16 in the cylinders. The outer end of one of the manifold units is provided with a plate or cover 64', while the opposite end of the manifold unit at the opposite end of the 10 engine receives a face plate 64", to which is connected an exhaust pipe 64". The flanges 65 at the ends are extended inward beyond the wall 64 and are integral with an exhaust housing 68 provided with an exhaust channel or passage 69 communicating by suitable openings 70 with the exhaust opening in the corresponding exhaust elbow. The upper surface of the manifold member is finished to receive the flanges 36 which are held in 15 place by suitable bolts or cap screws 71. Between the walls 64 and 68 there is a chamber 72 formed which constitutes a water jacket in communication with the openings 67 and with the jacket formed in the exhaust 20 elbow by suitable openings 73 in alignment with the openings 67 and with the jacket formed in the exhaust elbow by suitable openings 73 in alignment with the openings 39.

From this structure it will be seen that 25 the exhaust from the cylinders passes through the opening 69 and out at the end to the next manifold and that the circulating water to each pair of cylinders passes up from the inlet around the exhaust manifold from whence it passes to the head jacket structure and from each head it passes through the member 40 to a discharge connection 74 leading to a discharge manifold 75, the connection 74 being 30 secured by a flange 76 to the flange 41. The end of the manifold at the forward end of the engine is closed by a plate 77 bolted to the end of the exhaust manifold member, while the last exhaust manifold member is 35 connected to an exhaust pipe flange 78 in turn connected to an exhaust pipe 79 leading to any suitable exhaust. The water supply manifold pipe is connected by a suitable pipe 80 to a circulating pump 81 which is 40 supplied from a pipe 82 leading to any suitable source of water supply.

Cam shaft and valve operating structures.

Each of the cylinders is provided at a 45 point opposed to the exhaust with a finished boss 83 and it is upon these bosses of the several cylinders that the cam shaft bearing and trough structure is mounted. This cam shaft bearing and trough structure is 50 made up in sections in a manner similar to the exhaust, that is, it is made in sections one for each pair of cylinders, and each of these sections comprises a trough consisting of a bottom 84 provided with brackets 85 55 secured to the corresponding bosses 83. The

trough also includes a front side 86 and a rear side 87, the ends of each trough section being open. Within each trough are three bearings 88, there being one near each end and one between the two cylinders, and 60 these bearings support, so far as this section is concerned, a cam shaft 89 provided adjacent each cylinder with an exhaust cam 90, a primary fuel and air inlet cam 91 and 65 a main air inlet cam 92, these cams being 70 properly timed in order to bring about the proper operation of the engine. Secured upon the top of the trough section is a cover comprising a rear portion 93 and an outside portion 94, these two portions being 75 provided with notches 95 and upwardly extending flanges 96 above each of the cams to permit the entry of the depending portions 97 of the valve rocker arms 98. These 80 rocker arms are all alike and each is provided with a roller 99 for engaging the cam, and at its opposite end with an adjusting screw 100 for engaging the corresponding valve stem. In order to take up any lost motion between each roller 99 and 85 its cam, each of the rocker arms is provided with a spring 101 engaging a projection 102 on the underside of the arm and the corresponding portion of the cylinder head, the spring being prevented from buckling by 90 a suitable pin 103.

Each of the trough sections is further provided at its ends with flanges 104 secured together, and when so secured together they form a continuous trough and 100 support for the cam shaft throughout its entire length and the trough is closed in the case of the two end trough sections by a suitable plate 105 on the one end and a gear casing member 106 on the opposite end, this 105 gear casing being secured to or forming a part of the governor casing and being adapted to receive suitable gearing of any desired arrangement connected to the shaft 110 operating the governor so that the drive from the engine to the governor conveys the drive to the cam shaft.

Fuel supply.

Fuel supplied to the engine is delivered 115 under pressure to the mechanism for feeding it to the several cylinders, and any suitable means may be provided for supplying it in this manner, it being sufficient, so far as this application is concerned, to state 120 that the fuel is delivered under pressure to the feeding mechanism now to be described.

The trough member at the governor end of the engine is provided with a downwardly extending bracket 107 and above this member the side of the trough is provided with an opening 108. Secured to the bracket 107 and against the side of this trough section is a fuel pump housing 109 provided with 125 a cover plate 110 upon its front and a cover 130

plate 111 upon its top. Mounted within the upper part of the housing in a horizontal plane with the cam shaft and in parallel alinement therewith is a pump shaft 112 provided with a plurality of eccentrics 113 one for each cylinder, and with a driving gear 114 meshing with a driving gear 115, shown in dotted lines in Fig. 3, this gear 115 being arranged upon the cam shaft. Engaging each of the eccentrics 113 is an eccentric strap 116 pivotally connected to a pump plunger 117 passing through a suitable stuffing box 118 into a pump barrel 119 formed in the housing 109. It is obvious that there is an eccentric strap, plunger and barrel for each cylinder, and each of these barrels communicates by an opening 120 with an opening 121 in turn leading to a discharge check valve member 122 provided with an opening 123 having a check valve 124 therein. This opening 123 also communicates by an opening 125 with another check valve member 126 provided with a check valve 127, and the opening in this check valve member communicates with an opening 128 in a discharge member 129, the opening in this discharge member leading to a suitable connection 130 connected to a pipe 131 leading to the corresponding cylinder. It is preferable to arrange the check valves for the discharge of the several fuel pumps in bars to secure them in place by through bolts 132, as shown in Fig. 6. The port 120 of each fuel pump leads to a corresponding inlet port 133 arranged in a control valve bar 134 provided with a longitudinally disposed opening 135 for the reception of a gang valve member 136, this member being provided, in alinement with each hole, with an opening 137 so that by rotating the member 136 the passage at this point may be effected. One end of the gang valve member passes through a stuffing box structure 138 and outside of this structure the valve member is provided with an operating arm 139. Secured to the underside of the control valve bar is a check valve bar 140 provided with a plurality of check valves 141 similar to the discharge check valve. To the underside of this bar is another check valve bar 142 having check valves 143 and below this bar is a supply bar 144 provided with a longitudinal opening 145 having branch openings 146 leading to the several check valves of the bar 142. At the end this supply bar is provided with a supply connection 147. The control bar, the check valve bars and the supply bar are all secured to the housing by suitable through bolts 148 passing up into the lower part of the housing. The operating arm 139 is pivotally connected to a link 149 in turn pivotally connected at its upper end to a lever 150 having a forked end 151 engaging in the groove 7 of the governor.

Cam shaft oiling system.

The oiling system comprises any suitable pump arranged in the bath of oil in the crank case, but I have shown a gear pump 70 comprising a casing 152 provided with a stuffing box 153 receiving the vertical shaft 154 driven from the engine. On the lower end of this shaft is a gear similar to and meshing with the gear 154^a mounted in the pump case. Secured to the under face of the pump casing is a suitable plate 155. This pump receives oil on one side in an obvious manner and forces it into a supply pipe 156 which leads up through the casing 80 to a manifold pipe 157 arranged against the back wall 87 of the cam shaft trough. This manifold is connected by short connections 158 with each of the bearings 88. In operation, the oil pump elevates the oil to the bearings and as it escapes about the shaft 89 it collects in the trough and from there passes through the opening 108 into the fuel pump housing and rises to a level such that the upper surface is in the path of the cams 90 on the cam shaft. This level is maintained by a stand pipe 159 extending up through the bottom 85 of the trough and to a point near the bottom of the shaft 89. The lower end of this pipe 159 passes down to the crank case so as to deliver the overflow of oil back to the supply. 95

Complete operation.

Assuming that fuel under pressure is supplied to the connection 147 and that air under pressure is supplied to the port 51, and further assuming that there is some suitable means for turning the engine over initially, the rotation of the crank shaft causes the 100 rotation of the cam shaft, and this operation causes the rotation of the fuel pump shaft when by reason of the proper timing of the cam shaft and the fuel pump shaft, fuel will be forced under pressure to the opening 105 110 of the proper primary fuel and air inlet valve mechanism, whence the fuel and the preliminary air will be forced into the proper cylinder and the main air supply will be admitted through the main air valve 115 115 57 of that particular cylinder, this main air valve being opened by the rocker arm actuated by the cam shaft. Upon the compression stroke the fuel and air will be compressed to a very high degree of compression 120 when it will ignite and explode giving an impulse to the piston. In like manner the explosion, compression and exhaust with respect to the other cylinders follow in proper sequence, when the engine is in operation. During the operation of the engine the circulating pump forces water in separate branch systems to the cylinders, thence to the cylinder heads and from these heads out through the discharge. 125 130

- Having described my invention, I claim:—
1. In an internal combustion engine, a plurality of cylinders, each cylinder having a detachable head, a common exhaust manifold for said cylinders, a water jacket for each cylinder, a water jacket for each head, a water jacket for said manifold, and connections for circulating cooling medium from the jacket of each cylinder through the manifold jacket to the jacket of a cylinder head. 70
  2. In an explosive engine, a plurality of cylinders, a head for each cylinder, a water jacket for each cylinder, a water jacket for each cylinder head, a water-jacketed exhaust manifold member connected to a pair of cylinders, the water jacket thereof being connected to the water jackets of the corresponding pair of cylinder heads and to the cylinder water jackets and establishing communication between the jackets of the cylinders and the jackets of the heads, means for supplying water to each cylinder jacket, and means for leading the water away from each cylinder head jacket. 80
  3. In an explosive engine, a plurality of cylinders, each having an independent water jacket, a head for each cylinder having an independent water jacket, a plurality of water manifold sections, one for each pair of cylinders and each establishing communication between its pair of cylinders and the corresponding pair of cylinder heads, means for supplying circulating water to each cylinder jacket, and means for leading the circulating water from each cylinder head jacket. 90
  4. In an explosive engine, a cylinder, an independent water jacket for the cylinder, a detachable cylinder head, and an air intake and exhaust for the cylinder head, an independent water jacket for the cylinder head, a combined exhaust and water manifold structure detachably connected to the cylinder head and having an inner exhaust housing and a jacket therearound, connections between the water jacket of said structure and the water jackets of the cylinder and cylinder head, means for leading water to the cylinder jacket, and means for leading water from the cylinder head jacket. 100
  5. In an explosive engine, a plurality of cylinders, a water jacket for each cylinder, a head for each cylinder, a water jacket for each head, an exhaust and intake for each head, a combined exhaust and water manifold structure comprising a plurality of units, each consisting of a housing having an exhaust passage connected to the exhaust of the corresponding cylinder, the passages of all of said units communicating and a water jacket surrounding each unit structure, independent connections between the water jacket of each cylinder and its corresponding exhaust and water circulating manifold, connections 110
  - between the water jacket of said manifold and the corresponding cylinder head, means for supplying water to each cylinder jacket, and means for leading water from each cylinder head jacket. 120
  6. In an explosive engine, a cylinder, a water jacket therefor, a cylinder head having a water jacket, an air inlet housing provided in said head, an exhaust housing arranged in said head, an exhaust connection extending from said head and having a water jacket therearound communicating with the water jacket of the head, an exhaust and water manifold structure comprising an inner exhaust housing connected with the exhaust housing of the cylinder head, a water jacket surrounding the same and connected to the water jacket of the exhaust connection and to the water jacket of the cylinder, means for supplying water to the cylinder jacket, and means for leading water from the cylinder head jacket. 130
  7. In an explosive engine, a cylinder, an independent water jacket for said cylinder, a cylinder head having an exhaust opening and an air inlet opening, an air inlet housing communicating with said air inlet opening, an exhaust housing communicating with the exhaust opening and terminating in an exhaust connection outside of the cylinder head, a water jacket surrounding the head, the air inlet housing and the exhaust housing and also surrounding said exhaust connection, said jacket having openings extending through the end of the exhaust connection, an exhaust and water manifold structure comprising an inner exhaust housing communicating with the exhaust connection of the head and having a water jacket communicating with the cylinder water jacket and with the said opening of the head jacket, means for supplying water to the cylinder jacket, and means for leading water from the cylinder head jacket. 140
  8. In an explosive engine, a cylinder, a water jacket for said cylinder, a cylinder head having an exhaust opening and an air inlet opening, an air inlet housing communicating with said air inlet opening, an exhaust housing communicating with the exhaust opening and terminating in an exhaust connection beyond the head, and a water jacket surrounding the head, the air inlet housing and the exhaust housing and also surrounding said exhaust connection, said jacket having water circulating openings at the end of the exhaust connection, an exhaust and water manifold comprising an inner exhaust housing open at both ends, a water jacket surrounding said housing and closed at both ends, connections between said manifold and the water circulating openings of the exhaust connection, connections between the water jacket of said exhaust and water manifold and the cylinder water. 150

jacket whereby there is a circulation of water from the cylinder jacket to the jacket of the manifold and to the jacket of the head, means for supplying water to the cylinder jacket, and means for leading water from the cylinder head jacket.

In testimony whereof I affix my signature in presence of two witnesses as follows:

ALEXANDER WINTON.
